UNITED STATES PATENT OFFICE.

HENRY COLBECK MICHELL, OF TORONTO, CANADA.

PIPE OR BOILER COVERING.

SPECIFICATION forming part of Letters Patent No. 620,476, dated February 28, 1899.

Application filed January 8, 1898. Serial No. 666,073. (No model.)

To all whom it may concern:

Be it known that I, HENRY COLBECK MICH-
ELL, manufacturer, of the city of Toronto, in
the county of York, in the Province of Onta-
rio, Canada, have invented certain new and
useful Improvements in Pipe or Boiler Cov-
erings, of which the following is the specifica-
tion.

My invention relates to improvements in
non-conducting coverings for pipes and boil-
ers, &c.; and the object of the invention is
to devise a simple, cheap, and easily-made
non-conducting covering for heated surfaces,
especially pipes and boilers, which will have
a maximum non-conducting property; and it
consists, essentially, of a covering comprising,
preferably, concentrically-arranged flakes
of mica having the larger flakes to the outside
and graduated smaller toward the inside of
the covering, the covering being held intact
laterally and longitudinally by a suitable
binding medium impregnated into the outer
and inner surfaces of the mass of mica, so as
to form mound-like projections to hold the
mass securely in place both laterally and lon-
gitudinally, as hereinafter more particularly
explained.

Figure 1 is a cross-section of my non-con-
ducting covering applied to a pipe. Fig. 2 is
a longitudinal section through the line $x'y$,
Fig. 1. Fig. 3 is a perspective view of por-
tion of the mold by which my pipe-covering
is preferably formed, with a section of the
pipe-covering thereon. Fig. 4 is a detail of
portion of the mold for forming the inner
portion of the pipe-covering, showing such
mold in reverse position. Fig. 5 is a cross-
section showing an alternative form of mak-
ing my non-conducting covering. Fig. 6 is a
longitudinal section through the line $x'y'$,
Fig. 5.

In the drawings like letters of reference
indicate corresponding parts in each figure.

I first sprinkle, preferably upon a sheet of
paper or any suitable backing of the de-
sired length or width to completely cover the
interior of the mold A, mica in small flakes,
laminæ, or particles. I next sprinkle my
binding medium, preferably silicate of soda
in solution, upon the mica previously super-
imposed upon the sheet, so that the mass now
becomes soppy or spongy. The silicate of

soda in solution being very sticky becomes
impregnated or mixed with the mica. It may
be necessary to follow out the above steps 55
two or three times to attain the desired thick-
ness. This spongy or soppy layer I lift into
the mold and place it in concentric form, as
indicated at B. I then fill in flake-mica or
mica in lamina form C concentrically, as in-
dicated in Fig. 3, thereby forming multitu-
dinous air-spaces c. I preferably use larger
flakes at the outside, decreasing in size to-
ward the center. Upon the bottom of the
top D of the mold I preferably place a sheet 60
of paper E having, silicate of soda in solu-
tion mixed with mica, as hereinbefore de-
scribed as to the layer C, such layer F also
forming a soppy or spongy mass. Upon the
bottom of the mold, previously filled as here- 70
inbefore described, I turn the top, as indi-
cated in Fig. 3. It will thus be seen that the
concentrically-formed layers already in the
mold will become incorporated to some de-
gree with the concentrically-arranged layers 75
C, hereinbefore described, similar to what
the concentrically-arranged layers C will be-
come incorporated with the layers B, the sili-
cate permeating in both cases into the mica
flakes or laminæ. This permeation of the in- 80
ner strata of concentric layers of mica C with
the outer layers is effected in a peculiar man-
ner, as the silicate of soda in solution forces
itself irregularly into the interior strata. The
mold after the above steps are taken is put 85
into a furnace, which has the effect of burn-
ing the paper out and boiling the silicate. As
the silicate boils it bubbles up and cakes and
becomes hard and forms itself into a series
of irregular mound-like projections b, (see 90
Fig. 2,) which extend into the central layers
C and effectually key the mica flakes in po-
sition and prevent lateral or longitudinal dis-
placement.

Although I describe silicate of soda as the 95
preferable binding and locking medium for
the mica laminæ, it will be understood that
any other suitable non-combustible binding
medium may be employed.

In Figs. 3 and 4 I show the manner of mak- 100
ing one half of the pipe-covering, and the
other half (shown in Fig. 1) would be made
in the same manner. When the molds are
placed together and put in the furnace, the

skin formed by the silicate would be continuous alike around the concentric as well as the radial portions, thereby completely encircling the mica.

5 In Figs. 5 and 6 I show an alternative form, in which I use a mass C' of hollow particles of mica not necessarily concentric—in fact, mixed in any way. The outer and inner layers B and F of the mica, permeated with the silicate in this case, also form a series of mound-like irregular projections b and f, projecting inwardly into the mass of particles and effectually serving to key the mica both from longitudinal and lateral displacement. 10 The cover is formed in this case in the mold in the manner hereinbefore described, with the exception that there are no concentric layers. This keying of the mica in position allows of multitudinous air-spaces. In Fig. 15 20 these multitudinous air-spaces are formed between the concentrically-arranged flakes, as indicated, and being irregular and arranged concentrically they act like so many non-conducting deflecting-plates, which, in 25 the opinion of eminent scientists, accounts for the extraordinary heat-non-conductivity of this covering.

In Fig. 5, in which the alternative form is shown and which of course is a cheaper construction, the dead-air spaces are formed in the heterogeneously-mixed mass of particles C'. It will thus be seen that I utilize to a maximum extent the two greatest non-conducting agencies—viz., dead-air spaces and 35 mica.

What I claim as my invention is—

1. A non-conducting covering comprising a mass of mica particles, and a binding medium located outside of the mica mass having 40 projecting portions extending thereinto, substantially as described.

2. A non-conducting covering comprising a mass of mica particles, and a binding medium located on opposite sides of the mica 45 mass having irregular projections extending thereinto, substantially as described.

3. A non-conducting covering comprising a mass of concentrically-arranged flakes or laminæ of mica, and a binding medium located 50 outside of the mass having projecting portions extending thereinto, substantially as described.

4. A non-conducting covering comprising concentrically-arranged flakes or laminæ of mica forming multitudinous non-communicating interstices and a binding medium incorporated into the outer concentric flakes of mica and forming irregular mounds in the interior whereby the laminæ are keyed or locked in place as and for the purpose specified. 55

5. A non-conducting covering comprising concentrically-arranged flakes or laminæ of mica forming multitudinous non-communicating interstices and arranged with the larger 60 flakes to the exterior and decreasing in size to the interior of the covering and a suitable binding medium permeating the outer portion of the layers having projecting portions extending into the space between the flakes. 65

6. A non-conducting covering comprising the mass of concentrically-arranged flakes or laminæ of mica, comminuted flakes at the exterior of the mass of concentric flakes, and a binding material incorporated with the 70 comminuted flakes and extending in between the concentrically-arranged flakes, substantially as described. 75

7. A sectional cylindrical covering comprising laminæ of mica, the binding material at 80 the outside and inside of the same and on the adjacent abutting edges of the sections whereby the said sections of such covering are maintained in shape and fitted together as and for the purpose specified. 85

8. A method of forming a non-conducting covering for boilers and the like consisting in spreading upon suitable backings to form the outer and inner layers of the covering, a composition comprising a damp or wet binding 90 medium intermixed with mica particles, superimposing upon the outer layer flakes or laminæ of mica in concentric layers placing the inner and outer layers together to inclose the central laminæ and finally subjecting the 95 whole to a suitable drying process whereby the binding medium is hardened and permeates into the mass as and for the purpose specified.

HENRY COLBECK MICHELL.
